UNITED STATES PATENT OFFICE.

CHARLES T. SCHOEN, OF MOYLAN, PENNSYLVANIA.

METHOD OF MAKING WHEELS.

No. 848,927.

Specification of Letters Patent.

Patented April 2, 1907.

Application filed June 25, 1906. Serial No. 323,401.

To all whom it may concern:

Be it known that I, CHARLES T. SCHOEN, a citizen of the United States, residing at Moylan, in the county of Delaware and State of Pennsylvania, have invented a certain new and useful Improvement in Methods of Making Wheels, of which the following is a full, clear, and exact description.

In making wheels from blanks of wrought metal the operations of shaping the blank for the subsequent operations of shaping the wheel have been costly in time and labor, and where the blank has been sheared in order to make it circular and of approximate wheel size there has been considerable waste of metal.

In the present invention these expenses are practically eliminated, since the angular blank cut from rolled, preferably steel, stock is either of a size to be dropped into the pressing-dies or of such size as to require only the nipping off of its corners to permit it to be dropped in such dies, and it is of the approximate weight of the finished wheel, and then while plastic it is subjected to die-pressure on its flat sides, whereby it is caused to flow out and fill up the matrix. In this way a wheel may be produced with or without a flange and dished or coned or not, as desired, or a blank may be produced requiring to be rolled and dished or coned, if desired, in order to complete its finish or to have cogs or teeth cut in its rim to form a gear-wheel.

In the accompanying drawings, illustrating the invention, in the several figures of which like parts are similarly designated, Figure 1 shows a suitable blank in edge and plan views. Fig. 2 shows in plan view, full lines, the blank with its four corners nipped and indicating by dotted lines a die-matrix. Fig. 3 is a cross-section of the first-operation dies with their product between. Fig. 4 is a plan view of the product of the first-operation dies. Fig. 5 is a cross-section of the second-operation dies with their product between. Fig. 6 is a cross-section of the punched wheel. Fig. 7 is a cross-section of a pair of dies for dishing or coning the wheel with their product between. Fig. 8 is a cross-section of the product of the dies of Fig. 7. Fig. 9 is an elevation of the car-wheel of Fig. 5 or of Fig. 8 punched and ready for use or such other finishing as may be required to fit it for any special use. Fig. 10 is a cross-section of a pair of dies with their product between for forming a wheel or

blank that may be gear cut. Fig. 11 is a cross-section, and Fig. 12 is an elevation, of the product of the dies of Fig. 10.

The blank 1 of Fig. 1 is of selected rolled stock cut to size and free of imperfections. It is preferably of steel and is treated hot or in such a state of plasticity as to flow under the pressure of the dies. It may have its corners or angles nipped off, as seen in Fig. 2, or if the female die is large enough this nipping of the corners may be omitted. The blank is dropped into the female die 2 (shown in Fig. 3 and represented by the dotted circle in Fig. 2) and subjected to pressure by the male die 3, with the result that the metal is displaced to form the rudimentary hub 4, web 5, and rim 6. The female die has the peripheral wall 7 of equal height to the thickness of the blank and also has the outwardly-sloping annular projection 8, between which and the wall the rim is formed, and it also has the central projection 9, between which and the projection 8 the rudimentary hub is formed. The male die 3 has a flat portion 10, an annular sloping projection 11, complementary to projection 8, and a projection 12, complementary to projection 9. The metal of the blank is displaced by the projections and forced out radially by the sloping projections. The product of the dies, Fig. 3, is then transferred to and acted upon by the dies 13 and 14, Fig. 5, wherein the annular projections 15, 16 are flat and serve to flatten out the web, and cavities 17 and 18 are provided to form a flanged rim.

If the wheel is to be dished or coned, then there may be used after the dies of Fig. 5 or in place of them the pair of dies shown in Fig. 7, wherein 19 is a female die having the rim-high wall 20, rim-cavity 21, annular projection 22 of a profile to form and dish or cone the web, and the hub-cavity 23. The complementary male die 24 has the flat portion 25, web-forming projection 26, and hub-cavity 27. As indicated, this pair of dies may be used for a third operation upon the product of the dies of Fig. 5, or the operation performed by the two pairs of dies when used separately may be combined in the pair of dies of Fig. 7.

In operating the dies, Fig. 5 or Fig. 8, the blank is subjected to pressure sufficient to cause the metal to flow freely and assume the contour of the die-faces, filling out completely into a perfectly rounded and symmetrical wheel, which is afterward punched

to obtain the axle-hole and may be or not further treated by rolling, machining, milling, or other procedure in accordance with the requirements of the user. In point of fact the wheel as it comes from the dies of Fig. 5 or Fig. 8 with its axle-hole punched is finished.

If desired, the projections for forming the web may be sloped so as to make the web thinner next to the rim.

In making flangeless wheels for use as such or for cutting with gear-teeth the blank is treated as before, but the second operation dies, Fig. 10, are used instead of those shown in Fig. 5, or these dies may be used alone and the entire process carried out in them. These dies comprise the female die 28, having the rim-cavity 29 and the rim-high wall 30, the web-forming flat annular projection 31, and the hub-forming projection 32, and the male die 33, having a flat portion 34, coöperating with the rim-cavity 29, the flat annular projection 35, coöperating with the web-forming projection 31, and the projection 36, coöperating with the hub-forming projection 32. The product, Figs. 11 and 12, of these dies has its hub-hole punched out, and then its rim is finished for any desired purpose, but particularly may be cut with gear-teeth.

It will be observed that the die-pressure is brought directly upon the flat sides of the blank in its course of treatment, and the rounding of the product is effected by displacement or flowing of the metal by such pressure within the preformed cavities of the dies.

By the method described it is possible to

avoid the expense of rounding the blank by forging, and it is also possible to avoid the waste of metal by shearing it round. The wheel or blank is perfectly rounded in the dies by the pressure to which it is subjected.

The products of the process herein described form the subjects of separate cases of even date herewith, one of which since filing has become Patent No. 834,761, dated October 30, 1906, and the other is Serial No. 323,403.

What I claim is—

1. The method of making wheels having a hub, a web, and a rim, which consists in shearing from rolled metal stock an angular flat blank of the approximate weight of the finished wheel and subjecting the blank to pressure on its flat sides only in circular dies, within which dies the blank is circumferentially confined during the pressing operation.

2. The method of making wheels having a hub, a web, and a flanged rim, which consists in shearing from rolled steel stock an angular flat blank of the approximate weight of the finished wheel and subjecting the blank to pressure on its flat sides only in circular dies within which the blank is circumferentially confined during the pressing operation and dishing or coning the wheel while so confined.

In testimony whereof I have hereunto set my hand this 22d day of June, A. D. 1906.

CHARLES T. SCHOEN.
